Attest.

United States Patent Office.

MARTIN LANDENBERGER, OF PHILADELPHIA, PENNSYLVANIA.

Design No. 4,230, dated July 19, 1870.

DESIGN FOR A KNITTED FABRIC.

The Schedule referred to in these Letters Patent and making part of the same.

---

all whom it may concern:

Be it known that I, MARTIN LANDENBERGER, of Philadelphia, in the county of Philadelphia and State Pennsylvania, have invented and produced a new and original Design for Knitted Fabric, of which the following is a specification.

The nature of my design is fully represented in the accompanying photographic illustration, to which reference is made, and consists in a series of parallel separate kitted threads, *a*, enchain'd, as shown, and such chains connected at each stitch by filling-threads *b* passing across the series of chains, at right angles, and all as shown.

Any colors may be employed.

Claim.

I claim as my invention—

The design for knitted fabric, as shown and described.

In testimony whereof I have signed my name to this specification in the presence of two subscribing witnesses.

MAKTIN LANDENBERGER.
